UNITED STATES PATENT OFFICE.

JAMES WILKINSON, OF SCHENECTADY, NEW YORK, ASSIGNOR TO GENERAL ELECTRIC COMPANY, A CORPORATION OF NEW YORK.

ELASTIC-FLUID TURBINE.

1,021,754.

Specification of Letters Patent. Patented Mar. 26, 1912.

Application filed October 14, 1911. Serial No. 654,722.

To all whom it may concern:

Be it known that I, JAMES WILKINSON, a citizen of the United States, residing at Schenectady, county of Schenectady, State 5 of New York, have invented certain new and useful Improvements in Elastic-Fluid Turbines, of which the following is a specification.

My invention relates to an improvement in 10 compound elastic fluid turbines wherein the power absorbing apparatus is interposed between high and low pressure turbines and is mounted upon a shaft co-axial with the two turbine shafts and detachably connect- 15 ed to both. The power driven apparatus thus forms the connection between the two simple shafts of the compound turbine and, by the provision of couplings or friction clutches I am enabled to drive the apparatus 20 by either turbine or by both turbines, suitable supply and exhaust passages being provided to enable the motive fluid to flow either in series through both turbines or independently through each turbine to a sepa- 25 rate exhaust.

My invention further contemplates the provision of novel means for governing the supply of motive fluid to a compound turbine of the character described, wherein the 30 speed governor is driven from the shaft of the power absorbing apparatus and is adapted to be connected to the valve controlling the supply of motive fluid to the high pressure turbine or to both turbines when acting 35 in series, or to either turbine when acting independently.

My invention further comprises the details of construction and arrangement of parts disclosed in the accompanying drawings 40 wherein the invention is illustrated as a turbo-generator-unit, Figure 1, representing a side elevation of the apparatus as a whole, and Fig. 2, a bottom detail view of the cross connections between the high and 45 low pressure turbines, together with the intermediate auxiliary supply and exhaust ports.

Similar reference numerals refer to similar parts throughout the drawings. 50 In the form illustrated, my invention comprises a high pressure turbine 1 and a low pressure turbine 2 mounted upon a base 3 and provided with bearing pedestals 4 which support the shafts 5 and 6 which

are driven by the rotating elements acted 55 upon by the motor fluid in the turbines 1 and 2, respectively. As the rotating parts and internal construction of the turbines may be of any standard design, all the details illustrating the same are omitted from 60 the showing. The turbines 1 and 2 are spaced apart sufficiently to permit the interposition of a power absorbing apparatus such as an electric generator 7. This generator is also mounted upon the bed plate 65 3 and has its rotating parts supported by a shaft 8 co-axial with the shafts 5 and 6 and supported by a single bearing pedestal 9 also rising from the base 3. Friction clutches 10 and 11 controlled by the hand 70 levers 12 and 13, respectively, are adapted to couple the shaft 8 to either or both of the shafts 5 and 6. The revolving parts of the generator are overhung so that they may be safely supported from a single ped- 75 estal.

The initial high pressure supply of motive fluid is introduced through a passage 14 under the control of a valve 15 or other regulating apparatus, into the high pressure turbine 1 and is exhausted therefrom through the pipe 16. The pipe 16 is coupled to a valve casing 17 carrying a valve 18 operated by the hand wheel 19 and adapted to control the connection between the exhaust pipe 16 80 and the four-way coupling 20. This coupling connects with a governing valve casing 21, which in turn is connected to a second valve casing 22, similar to 17, and provided with a valve 23 operated by a hand wheel 90 24 and adapted to control the communication between the main coupling 20 and the supply pipe 25 leading to the low pressure turbine 2. The motive fluid after flowing through this latter turbine is exhausted 95 through the passage 26 to a condenser 26 or other receptacle. High pressure motive fluid may be admitted to the coupling 20 through the pipe 27 under the control of a valve 28 adapted to be operated by the hand 100 wheel 29. An auxiliary exhaust pipe 30 leads from the coupling 20, the valve 31 being provided to close this opening, which valve is operated by hand in the same manner as the valve 28. The pipes 27 and 30 are 105 shown broken away in Fig. 2 of the drawing so as to illustrate the valves. A valve 32 is disposed in the valve casing 21 and is adapt-

ed, under the control of a speed governor, to regulate the admission of the motive fluid to the low pressure turbine 2.

Since it is my purpose to adapt the power absorbing apparatus to be driven by either of the turbines, I have mounted the centrifugal governor 33 upon the bearing pedestal 9 and connected it by any suitable speed reducing gearing to the generator shaft 8.

10 The governor acts to rock the bell-crank lever 34, the upper end of which is connected by a rod 35 and crank 36 to the high pressure admission valve 15. The lower portion of this lever is connected by the rod 37 and 15 crank 38 to the valve 32. Each of the rods 35 and 37 is provided with a yoke portion 39 which is adapted to be detachably connected to a stud or pin, located at the end of each arm of the lever 34. According to this 20 arrangement either rod 35 or 37, or both, may be readily connected and disconnected to the governor actuated crank 34 for the purposes hereinafter described. The clutch levers 12 and 13 are connected in the usual 25 manner to the clutch members 10 and 11 and are pivotally mounted upon brackets 40 and 41 connected respectively to the dynamo casing and to the pedestal 9.

As illustrated, the valves 18 and 23 are 30 open and the valves 28 and 31 are closed. The governor actuated valve 32 is disconnected from the governor, and the latter acts through the valve 15 to control the supply of motor fluid to the turbine 1.

35 In operation, the motive fluid passes through the high pressure turbine and cross pipe connections and through the low pressure turbine to the exhaust 26. Both clutches being closed the dynamo is driven 40 by both turbines. This is the normal manner of operation for the turbo-generator-apparatus and particularly under full load conditions. By closing valve 23, opening valve 31 in the auxiliary exhaust and releasing clutch 11, the high pressure turbine 1 will drive the dynamo. By releasing or 45 opening clutch 10, closing clutch 11, closing the valves 18 and 31, and opening valves 23 and 28, the high pressure fluid will act in the 50 turbine 2 to drive the dynamo, the supply being controlled by the valve 32 whose operating rod 37 is connected to the governor actuated crank 34 while the valve rod 35 is disconnected therefrom. By closing both 55 clutches, opening all of the valves except the auxiliary exhaust 31, and connecting both governor actuated valve rods to lever 34, the compound turbine will operate with a governed overload supply for the low pressure 60 turbine, which overload supply is controlled by the valve 32. There are many obvious advantages which would arise in common practice from these various methods of operating the compound turbine, such as enabling either machine to be repaired without 65

cutting the generator out of service; giving a variety of driving effects to the generator by the manipulation of the valves and clutches; and the simplifying to the greatest degree of the shaft construction and the governing apparatus for a compound turbine having so many different functions. 70

Obviously any character of controlling mechanism may be utilized for both turbines and the valves, clutches and cross pipe connections may be variously modified to suit different conditions. 75

In accordance with the provisions of the patent statutes, I have described the principle of my invention, together with the apparatus which I now consider to represent the best embodiment thereof; but I desire to have it understood that the apparatus shown is only illustrative and that the invention can be carried out by other means. 80

What I claim as new and desire to secure by Letters Patent of the United States, is,

1. The combination with a compound turbine, of a power absorbing apparatus interposed between portions of the turbine, and means for connecting and disconnecting said apparatus and turbine so that the former may be driven by either or both portions of said turbine. 85

2. The combination with a turbine having rotatable elements disposed in two separate casings, of a power absorbing apparatus disposed between said casings, a shaft for said apparatus, rotatable elements in each casing, shafts therefor, and couplings to couple said elements through the shaft of said power absorbing apparatus. 95

3. A turbo-generator-unit comprising a high pressure turbine, a low pressure turbine, motive fluid connections whereby said turbines are adapted to operate in series, a rotor for each turbine, a generator disposed between said turbines and having its rotatable parts co-axial with the rotors of said turbines, and means to connect said rotatable parts to said rotors. 105

4. An elastic fluid turbine apparatus comprising in combination, a plurality of turbines connected up to act in series, an interposed power driven apparatus interposed between two of said turbines, means to drive said apparatus from either turbine, a device responsive to the speed of said power driven apparatus, and means controlled thereby to regulate the supply of fluid to said turbine. 115

5. In combination, a high and low pressure turbine connected up to act in series, a power absorbing apparatus interposed between said turbines, and clutch means to couple said apparatus to either or both turbines. 120

6. The combination with two turbines connected up to act in series and having their shafts disposed in alinement, of a rotary power absorbing device disposed be- 130

tween said turbines and having a shaft also in alignment with said turbine shafts, clutch means to couple said turbines to said apparatus, valve means to control the supply of motor fluid to said turbines, and a speed governor which regulates the supply and is driven from the shaft of the power absorbing apparatus.

7. The combination with two turbines connected up to operate in series, of power transmission means, clutches to couple each turbine to said means, independent controlling mechanisms for each turbine, and a common governor for said mechanisms.

15 8. The combination with two turbines connected up to operate in series, of power absorbing means, clutches to couple each turbine independently to said means, independent controlling mechanisms for each turbine, a governor, and means to disconnect either of said controlling mechanisms from said governor.

9. The combination with two turbines connected up to operate in series, of power transmission means, clutch connections to detachably couple each turbine to said means, independent controlling mechanisms for each turbine, a governor, means to simultaneously connect both controlling mechanisms to said governor, and means to introduce an overload supply for the low pressure turbine which is acted upon by the controlling mechanism therefor.

30 10. The combination with two serially connected turbines, one of which normally operates at low pressure, of means to admit high pressure fluid to said low pressure turbine, and a controlling apparatus which regulates the admission of said high pres-

sure fluid and the exhaust fluid from the high pressure turbine responsive to variations of speed of said low pressure turbine.

11. In combination, two serially connected turbines in separate casings, a cross connection between said casings, two valves in said connection, a valve controlled supply and a valve controlled exhaust-port in said connection intermediate said valves, and an independent controlling mechanism for each turbine, substantially as described.

15 12. The combination with a high pressure turbine, a low pressure turbine and a cross connection whereby said turbines receive motive fluid in series, of a power absorbing apparatus adapted to be independently driven by either of said turbines, valve means to disconnect said turbines, an auxiliary valve controlled exhaust port for the high pressure turbine, a valve controlled supply port for the low pressure turbine, and independent speed responsive means to control the admission of motor fluid to either or both turbines, substantially as described.

20 13. The combination with a high pressure turbine and its shaft, a low pressure turbine and its shaft, a generator having its rotating parts driven by a shaft co-axial with said turbine shafts, and two friction clutches which act to connect said generator shaft to each of said turbine shafts, substantially as described.

25 In witness whereof, I have hereunto set my hand this 13th day of October, 1911.

JAMES WILKINSON.
